UNITED STATES PATENT OFFICE.

FREDERICK E. STANLEY, OF WATERBURY, CONNECTICUT, ASSIGNOR TO SCOVILL MANUFACTURING COMPANY, OF WATERBURY, CONNECTICUT, A CORPORATION OF CONNECTICUT.

BUTTON-FEEDING MECHANISM FOR BUTTON-SETTING MACHINES.

1,177,906.

Specification of Letters Patent.

Patented Apr. 4, 1916.

Application filed August 5, 1915. Serial No. 43,850.

To all whom it may concern:

Be it known that I, FREDERICK E. STANLEY, a citizen of the United States, residing at Waterbury, in the county of New Haven 5 and State of Connecticut, have invented a certain new and useful Improvement in Button-Feeding Mechanism for Button-Setting Machines, of which the following is a full, clear, and exact description.

10 This invention relates to the type of button-setting machine illustrated in the case of Stanley and Leggett, filed May 10, 1915, Serial No. 27,042, and has special reference to the button-turning feature by which the 15 buttons, as they come one by one from the hopper or turret through the raceway or chute in an edgewise position, are given a quarter turn so as to present them horizontally to the means by which they are placed 20 in operative relation to the tack or other fastening for attachment to a garment or other article.

The invention consists in the means by which the slotted cylindrical piece of the 25 button turner is given its turning movement to turn the button from its edgewise position into the horizontal position required in order to receive ultimately the tack or rivet by which it is set, said means comprising a spiral groove, preferably on the cylindrical 30 piece, and a reciprocating collar engaging said spiral groove, as I will proceed now to explain and finally claim.

In the accompanying drawings illustrating the invention, in the several figures of 35 which like parts are similarly designated, Figure 1 is a side elevation of sufficient of a button-setting machine of the type referred to to illustrate the application of the 40 present invention. Fig. 2 is a top plan view of the parts above the tack mechanism. Fig. 3 is a front elevation of the button turner detached, with the collar in vertical section. Fig. 4 is a cross-section of the collar and 45 cylindrical piece. Fig. 5 is a perspective view of the button turning or righting cylinder and the button ejector detached.

The head 1 of the machine supports the main shaft 2, and a button turret (not 50 shown) from which a button chute 3 descends, and a tack or rivet turret (also not shown) from which the chute 4 descends, all of which may be as in the case hereinbefore referred to. At the delivery end of the but-

ton chute is an auxiliary chute 5 having a 55 transversely arranged cut-off or escapement 6 reciprocated longitudinally by an elbow lever 7 actuated in any suitable way from the main shaft, as by a cam slide 8 and a cam 9, the slide being returned by any suitable means, such as a spring 10. The lower end of the auxiliary chute has a partible housing 11 in which is mounted the slotted cylindrical piece 12, as in the case referred to, or otherwise, so that it may be given a 60 quarter turn to present its slot 13 first vertically to receive the button edgewise from the chute, and then horizontally, so that it may be moved or transferred thence to the means by which it is presented to the attaching 65 agencies. This turning movement of the cylindrical piece is effected by providing it with an extension 14 projecting outside of the housing and having a quick-pitch spiral groove 15, or several of them, and on this 70 extension is mounted a collar 16 having a suitable connection with the groove 15 of the extension 14, such for instance, as the stud 17, so that as the collar is moved longitudinally of the extension, the turner will be 75 turned or rotated on its axis. This movement of the collar may be effected in a number of ways, as for example, by providing a stud 18 on the collar which is engaged by a lever 19 pivoted at 20 on a bracket 21 of the 80 head, said lever 19 being extended rearwardly and provided with a cam roller 22 engaged by a cam 23 on the main shaft 2, so as to move said lever, which motion is converted into a reciprocating motion of the 85 collar in the direction of the length of the extension 14. The return movement of the lever may be effected in any suitable way, as by spring 24. The turner is fixed in the 90 housing, against longitudinal movement 95 therein in any suitable way that will permit of its rotary movement therein.

The cylindrical piece is bored longitudinally, and this bore serves to support an 100 ejector rod 25 having a head 26 which extends into the slot 13, the other end of the rod being provided with a grooved collar 27 adjustable thereon in any suitable manner, and this collar is engaged by a tracker 28 swiveled on the end of a lever 29 which is 105 pivoted at 30 to the bracket 21 and extends thence rearwardly and is provided with a cam roller 31 which is engaged by a cam 32

on the main shaft 2, so as to impart motion to said lever 29 in one direction, the movement of said lever in the other direction being effected by any suitable means, such as the spring 33, and these motions of the lever are converted into a horizontally reciprocating motion of the rod 25.

By the described mechanism, a button falling from the button turret into the chute 10 3 is dropped into the slot 13 in the button turner in advance of the head 26, and then the cylindrical piece is given a quarter turn by the movement of the collar 16 so as to turn the slot from the vertical into the horizontal, and thus turn the button from an edgewise position into a horizontal position such as it must be given in order to be properly set on the goods. When the turner is thus turned, the rod 25 is moved longitudinally of the cylindrical piece so that its head will act upon the horizontally arranged button in the slot 13 and eject it, delivering it to any suitable holding mechanism by which it is presented to the tack or rivet applying mechanism for attaching the button to the goods, or in other words, setting.

The mechanism described for effecting the turning of the button turner so as to right the button is simple in construction and operation, and is particularly meritorious because of its simplicity and directness in operation.

Variations in the construction and arrangement of parts are possible and permissible within the scope of the invention as 35 herein claimed.

What I claim is:—

1. In a button setting machine, a button turner fixed in its longitudinal relation and capable of rotation on its longitudinal axis 40 and having a spirally grooved extension, a collar applied to said extension and engaging said spiral groove, and means to move said collar longitudinally of the extension to thereby turn to rotate the turner.

45 2. In a button setting machine, a button turner fixed in its longitudinal relation and capable of rotation on its longitudinal axis and having a spirally grooved extension, a collar applied to said extension and engaging 50 said spiral groove, and means to move said collar longitudinally of the extension to thereby turn or rotate the turner, combined with an ejector arranged in said turner and movable back and forth therein in the direction of its length.

Copies of this patent may be obtained for five cents each, by addressing the "Commissioner of Patents, Washington, D. C."

3. In a button setting machine, a button turner fixed against longitudinal movement and capable of turning on its longitudinal axis and having one end slotted transversely to form a button receiving and turning cavity and having a quick pitch spiral groove at its other end, a collar mounted upon the grooved end of the turner and engaging said groove, and means for bodily moving said collar lengthwise on the turner whereby the 65 turner may be rotated so as to present its slot vertically to receive a button and then horizontally to admit of the discharge of the button from the turner.

4. In a button setting machine, a button turner fixed against longitudinal movement and capable of turning on its longitudinal axis and having one end slotted transversely to form a button receiving and turning cavity and having a quick pitch spiral groove at 75 its other end, a collar mounted upon the grooved end of the turner and engaging said groove, and means for bodily moving said collar lengthwise on the turner whereby the turner may be rotated so as to present its 80 slot vertically to receive a button and then horizontally to permit the discharge of the button, combined with a longitudinally reciprocating button ejector arranged in said turner.

5. In a button setting machine, a button turner, a housing in which it is mounted and capable of turning on its longitudinal axis and having one end slotted transversely to form a button receiving and turning cavity 90 and having a quick pitch spiral groove at its other end, a collar mounted upon the grooved end of the turner and engaging said groove, and means for bodily moving said collar lengthwise on the turner whereby the 95 turner may be rotated so as to present its slot vertically to receive a button and then horizontally to permit the discharge of the button, combined with a button ejector arranged in said turner and means to move 100 said ejector longitudinally in said turner to discharge the button from the turner.

In testimony whereof I have hereunto set my hand this twenty-ninth day of July A. D. 1915.

FREDERICK E. STANLEY.

Witnesses:

SADIE CORRIGAN,
GLADYS ROBERTSON.

It is hereby certified that in Letters Patent No. 1,177,906, granted April 4, 1916, upon the application of Frederick E. Stanley, of Waterbury, Connecticut, for an improvement in "Button-Feeding Mechanism for Button-Setting Machines," an error appears in the printed specification requiring correction as follows: Page 2, line 44, claim 1, for the word "to" read *or*; and that the said Letters Patent should be read with this correction therein that the same may conform to the record of the case in the Patent Office.

Signed and sealed this 18th day of April, A. D., 1916.

[SEAL.]

R. F. WHITEHEAD,

Acting Commissioner of Patents.
